UNITED STATES PATENT OFFICE.

CHARLES A. ROLFE, OF REDLANDS, CALIFORNIA.

GOLF GAME.

1,338,963.

Specification of Letters Patent.

Patented May 4, 1920.

Application filed April 22, 1918. Serial No. 230,016.

To all whom it may concern:

Be it known that I, CHARLES A. ROLFE, citizen of the United States, residing at Redlands, in the county of San Bernardino, 5 State of California, have invented new and useful Improvements in Golf Games, of which the following is a specification.

This invention relates to golf games and relates particularly to a game of golf which 10 may be played within a restricted space. It further relates more particularly to a game affording putting practice for the standard outdoor game of golf.

In my new game of golf I utilize a ball- 15 trap similar to that shown and described in my U. S. Letters Patent No. 1,208,838, dated Dec. 19, 1916; and I use this trap in conjunction and combination with a playing surface laid out and played upon in such a 20 manner as to afford a zestful game and also to afford excellent putting practice.

The whole invention will be best understood from the following detailed description of a preferred form of game apparatus, 5 reference for this purpose being had to the accompanying drawings in which—

Figure 1 is a plan of the game apparatus; Fig. 2 is a side elevation of a part thereof; and Fig. 3 is an enlarged vertical section 30 showing the trap.

In playing my game any suitable playing surface may be provided; and for convenience I provide an elongated strip of canvas C which may be provided with a roll 35 10 at one end on which the canvas may be rolled, and adapted to form a back stop behind the trap T.

The target, which surrounds the object (the trap) at which the ball is putted and 40 15 in which target the ball must come to rest in order to "count" at all, comprises an outer square surface 11 and then a series of concentric annular surfaces 12, 13 and 14 and an inner circular surface or space 15, which 45 space 15 is occupied by the trap T. These spaces may be delineated upon the canvas surface by having their outlines painted or otherwise colored or marked, as indicated at 20; or the different surfaces may be 50 colored in different colors. At a distance of say 45 inches from the target there is a tee position 25, marked by a colored circle, or some similar marking, and preferably with a line or band of color or other marking at 55 26 immediately behind. At a distance of say 90 inches there is a similar tee position

and then again there may be the same at a distance of say 130 inches. Shots are made at the trap in the center of the target from the various tees. Various methods may be 60 used for scoring; preferably a method which will give the highest number of points for the performance which is best when judged from the standpoint of standard golf play. Thus the following method may be used: 65 A game may be played by taking a certain number of shots from each tee, say five shots from each tee, and then totaling the number of points obtained. If the ball lies outside the target it counts for nothing; and as 70 many points are counted as are indicated on the several target spaces, depending upon which target space the ball comes to rest on. If the ball is putted into the trap, it counts for the maximum of five points. If, however, 75 the ball is putted too hard, and upsets the putting trap, it then counts for nothing.

The putting trap is so constructed as to catch and hold any ball coming at proper speed within its boundary; and it is preferably made of the same diameter as a standard golf hole. The general construction and operation of this putting trap are set forth in my Letters Patent hereinbefore referred to. If the ball is putted so hard that 80 it would pass over the standard golf hole, then it will also overturn the trap; in which case the putt counts for nothing. The trap comprises a suitable circular head or framework 30 carrying a series of pendant wires 90 or the like 31 inside a rim 32. The framework 30 is carried on a column or post 33 carried on base 34; and the pendants are carried at such a height that their lower ends are struck and swung inwardly by a 95 ball, allowing the ball to pass inwardly inside the ring of pendants. However, the pendants cannot swing outwardly (due to the rim 32) and a ball which has once passed inside the ring of pendants cannot pass out 100 of the trap again unless it is traveling with such speed and force as to overturn the trap. The base 34 is made of just the proper size to allow the trap to be overturned when the ball is traveling with such speed 105 and force that it would ordinarily pass over the standard golf hole. Furthermore, the trap will not catch a ball which would in the standard game "rim" the hole.

It will be seen that my game comprises 110 essentially the combination of a surface having superficial markings and delineations

into which a ball may be rolled, and having also at its center, or objective point, a trap which will trap the ball if it is putted at the trap and at proper speed; this trap having 5 also the faculty of releasing the ball (by upsetting) if the ball is putted with too great force. It is to this combination that the following claims are generally directed, without being specifically or entirely limit- 10 ed to the particular details herein set forth.

Having described a preferred form of my invention, I claim:

1. In combination, a flat flexible playing surface, a mechanical trapping means for a 15 ball situated on said surface and being entirely above said surface, said trapping means being adapted to release a ball if driven therein with a force exceeding a predetermined degree, markings on said surface 20 surrounding the trapping means and delineating objective surfaces into which a ball may be rolled, and markings at differently spaced points from said trapping means to indicate "tee" positions for a ball.
- 25 2. In combination, a flat flexible playing surface adapted to be compactly rolled and

having thereon markings delineating objective surfaces into which a ball may be rolled and a mechanical trapping means for a ball situated within said delineated surfaces and entirely above said playing surface and being freely removable therefrom, said mechanical trapping means being capable of releasing such ball if driven into it with an excessive force. 30

3. In combination, a flat flexible playing surface adapted to be compactly rolled, a removable mechanical trapping means for a ball situated on and entirely above said surface, said trapping means being capable of 40 releasing such ball if driven into it with a force exceeding a predetermined degree and a backstop adjacent said trapping means adapted to serve as a means about which the playing surface may be rolled. 45

In witness that I claim the foregoing I have hereunto subscribed my name this 16th day of March, 1918.

CHARLES A. ROLFE.
